CLAIM

The ornamental design for a hand-held transmitter for remotely controlling a security alarm system, as shown and described in the drawings.

DESCRIPTION

FIG. 1 is a front and upper left perspective view of a hand-held transmitter for remotely controlling a security alarm system showing our new design with the actuator rotated to the off position;

FIG. 2 is a right side elevational view thereof, the left side elevational view thereof being a mirror image except for the actuator;

FIG. 3 is a top plan view thereof with the actuator rotated to the arming position;

FIG. 4 is a top plan view thereof with the actuator rotated to the disarming position;

FIG. 5 is a top plan view thereof with the actuator rotated to the off position;

FIG. 6 is a front elevational view therof with the actuator rotated to the off position;

FIG. 7 is a rear elevational view therof with the actuator rotated to the off position; and,

FIG. 8 is a bottom plan view thereof.
